US0D1084976S

(12) **United States Design Patent** (10) **Patent No.:** **US D1,084,976 S**
(45) **Date of Patent:** **** Jul. 22, 2025**

(54) **RECHARGEABLE BATTERY**

(71) **Applicant:** **SHENZHEN KINGFISH ELECTRONICS TECHNOLOGY CO., LTD**, Shenzhen (CN)

(72) **Inventors:** **Xingang Jiang**, Xincai (CN); **Jian Chen**, Shenzhen (CN)

(73) **Assignee:** **SHENZHEN KINGFISH ELECTRONICS TECHNOLOGY CO., LTD**, Shenzhen (CN)

(**) **Term:** **15 Years**

(21) **Appl. No.:** **29/838,763**

(22) **Filed:** **May 16, 2022**

(30) **Foreign Application Priority Data**

Nov. 17, 2021 (CN) 202130753555.4

(57) **CLAIM**

The ornamental design for a rechargeable battery, as shown and described.

DESCRIPTION

FIG. 1 is a first perspective view of a rechargeable battery showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate portions of the article that form no part of the claimed design.

1 Claim, 8 Drawing Sheets
